UNITED STATES PATENT OFFICE.

CHARLES R. UHLMANN, OF PEORIA, ILLINOIS.

ESCUTCHEON.

SPECIFICATION forming part of Letters Patent No. 532,223, dated January 8, 1895.

Application filed March 26, 1894. Serial No. 505,091. (No model.)

To all whom it may concern:

Be it known that I, CHARLES R. UHLMANN, a citizen of the United States, residing at Peoria, in the county of Peoria and State of Illinois, have invented certain new and useful Improvements in Escutcheons; and I do hereby declare that the following is a full, clear, and exact description of the invention, which will enable others skilled in the art to which it appertains to make and use the same.

This invention relates to improvements in escutcheons.

The object of the invention is to provide an escutcheon with means to prevent a door being opened either by the turning of the knob or by the picking of the lock.

In the drawings herewith, Figure 1 represents a rear view of an escutcheon showing a plate in two positions as swinging on its pivot. Fig. 2 is also a rear view of the escutcheon shown in Fig. 1 with the plate removed. Fig. 3 is a view of the plate used in the escutcheon showing its construction. Fig. 4 is a sectional end view of the escutcheon plate through line xx Fig. 2. Fig. 5 is a rear view of an escutcheon, partly broken away, showing the locking of the knob and the key at the same time. Fig. 6 is a rear view of an escutcheon showing a modified form of construction.

30 A in the several figures represents the body of the escutcheon with a flange or wall around its edges to form an inclosure for the working parts.

B represents a locking plate preferably of sheet metal which has a pivotal connection with the plate A by a post C on the said plate. At D is also a post secured to the plate A which is used as a guide and for holding and steadyng the plate in its movements.

40 The locking plate B is perforated at C' and D' with holes slightly larger than the diameter of the posts C and D, which open into smaller perforations C² and D² respectively, having a narrow neck between the holes smaller than the said holes or perforations C² and D². The said posts C and D are undercut as at D in Fig. 4 leaving the head as shown. The method of placing the plate B in position may now be understood. The posts C and D are let 50 through the holes C' and D' respectively in the said plate B and the plate is then forced

downward and thus allowing the posts to enter the smaller holes C² and D², which just fit the necks of the posts and the heads of said posts retain the plate in its position and a slot 55 D³ is cut in the plate B at one side of the post D to allow the plate to swing on the pivot formed by the post C.

A hole E is cut in the plate B for the introduction and operation of the knob-rod E'. 60 The said hole E is filed away at one side to form the triangular indentation at F in the several figures; the purpose of which will be hereinafter described.

The plate B extends downward past the key-hole E² and an opening E³ is made in the said plate to correspond with the said key-hole and a slot E⁴ is cut in the plate at the side of the hole E³ to engage the key E⁵.

The upper portion of the plate B terminates 70 in a tongue B' which communicates with a horizontal slot I in the escutcheon by a knob I' which reaches through the slot to the front face of the device, and which is moved by the hand. A slot G is also cut in the escutcheon 75 plate preferably at right angles to the slot I and a knob H engages therewith.

The object of the invention being known the operation may be understood from the following:—In Fig. 1 the plate is shown in 80 solid lines engaging a key while the door-knob may be turned without trouble, but if now the knob H be raised and the plate thrown to the left, as shown by dotted lines (and the knob H allowed to drop to hold it in place) 85 the key-hole will be free and the knob-rod engaged so that it cannot possibly be turned.

Fig. 5 shows the parts as hereinbefore described, but showing the triangular indenture F on the opposite side of the hole to that shown 90 in Figs. 1 and 3 and which has the effect of locking the key and the knob simultaneously as shown in solid lines. By locking the knob the bolt is held against being drawn into the lock.

In Fig. 6 is a modified form of the invention and in which the plate B is cut away at one side and is replaced by a catch J having a notch K as shown and which catch is pivoted near its upper extremity to the plate B at K' 100 and a wedge L hangs in a vertical slot N in the plate B by a pin M so that when the wedge

is let downward it occupies the space between the said catch J and the wall of the escutcheon plate.

When the wedge is raised the knob rod E' 5 may be readily turned; the catch J giving at every movement. This forms a very simple, efficient device for the purpose. Therefore the knob is locked perfectly. When the catch is raised as shown in dotted lines, the knob 10 is entirely free. The wedge may be retained in its upper position by any good means and when lowering, the catch falls into place very readily. By this construction the key-hole may be opened and closed at will without the 15 knob being interferred with in any way. At the same time the knob may be engaged independently of the remainder of the device. By these means herein described any door 20 may be provided with a cheap and efficient device which cannot be tampered with from the outside. This device may also be placed with a lock without trouble.

Having described my invention at length, what I now claim, and desire to secure by Letters Patent, is—

1. An escutcheon having means for locking the knob spindle and key simultaneously or separately and consisting of a locking plate

B pivotally secured within the escutcheon and having a slot at its lower end for engagement with the key E, the upper extremity of said plate terminating in a tongue B' carrying a knob I for engagement with a slot I' in the escutcheon, a knob H adapted to slide in the slot G of the escutcheon to engage the said tongue B', a catch J pivotally secured on the escutcheon and adapted to engage and hold the knob spindle against being turned, and a movable stop L so placed with reference to the catch J as to prevent said catch being 40 moved by the knob spindle whereby the knob spindle is held against being moved.

2. An escutcheon having a locking plate pivoted thereon substantially as set forth in combination with a catch J pivotally hung on 45 said escutcheon for engagement with the knob-rod, a wedge L mounted on the escutcheon and having a sliding connection therewith and adapted to lock the catch J and the knob-rod E' substantially as set forth.

In testimony whereof I affix my signature in presence of two witnesses.

CHARLES R. UHLMANN.
